UNITED STATES PATENT OFFICE.

WILLIAM W. DILL, OF SEATTLE, WASHINGTON.

AMALGAMATOR.

1,230,135.

Specification of Letters Patent. Patented June 19, 1917.

Application filed October 23, 1916. Serial No. 127,253.

To all whom it may concern:

Be it known that I, WILLIAM W. DILL, a citizen of the United States, residing at Seattle, in the county of King and State of Washington, have invented certain new and useful Improvements in Amalgamators, of which the following is a specification.

This invention relates to amalgamators of the class used in separating precious metals from their ores. Its object is to render the process of separation thorough and expeditious and to economize manual labor. To this end, my invention consists in the construction and combination of parts forming an amalgamator hereinafter more fully described, and particularly stated in the claims, reference being had to the accompanying drawing, in which—

Figure 1, represents a longitudinal, vertical section at line x, x , Fig. 2, of an amalgamator according to my invention.

Fig. 2, is a plan or top view of the same.

Fig. 3, shows a transverse vertical section at line y, y , Fig. 1.

Numeral 4 represents a hydraulic table or sluice box mounted on legs 5, at an incline down which the slush of water and pulverized ore will run by gravity. A series of crossbars 6, called a mining riffle, are located across the bed of the table near the head. The remainder of the table is covered with a sheet of copper 7, which extends beyond the lower end 8, and depends therefrom slanting back at an acute angle under the said end, its lower edge 9, being directly over the trough 10. This trough is located below and a little back of the delivery end 8, so that anything falling freely or running from the end 8, will pass over the trough and not be caught by it. The trough slants to deliver to one side at 11, into any suitable receptacle. A series of crossbars 12, rest removably in notches in the sides 13, of the table, and each crossbar carries a series of plates 14, preferably of copper silver plated, depending to the table plate 7, for gathering metal. These gathering plates are located with spaces of about their own width between them upon each bar 12, and the plates on adjacent bars alternate so as to locate the plates of one bar opposite the spaces between the plates of the next bar in lines along the table.

The ends of the plates 14, come in contact with the table plate 7, on lines 15, preferably oblique to the line of the table; those

on one bar slanting to the right and those on the next bar slanting to the left. A hamper-board 16, is hung to swing on trunnions 17, in the sides 13, of the table. This amalgamator is adapted for service in quartz milling, in mining dredging and in hydraulic placer mining. The ore is first to be crushed and pulverized by any suitable means to the finest condition practicable. The mercury or amalgamating compound is applied by throwing it against the front faces of the gathering plates 14; its chemical affinity for the copper and silver causing it to adhere and spread over them.

Enough mercury is applied to run down upon the table plate 7, and cover it. The pulverized ore is to be mixed with water forming slush that is delivered onto the riffle 6, by any usual means, such as a flume running to the head of the table. The bars of the riffle stop such particles of metal as are too heavy to flow over them suspended in the water as the slush moves down the incline of the table.

In its progress, the slush comes in contact with the gathering plates 14, which present their whole immersed surfaces to catch the fine particles of metal which flow against them. At the same time, the oblique ends 15 steer the slush from side to side crosswise of the table so that the entire surface of the plate 7 is employed in gathering the particles of metal that sink to the bottom of the moving slush. When the mercury becomes loaded with metal it forms into the little globules peculiar to mercury and is readily carried by gravity and the friction of the moving slush upon it down the incline, and its native adhesion to the copper plate causes it to follow the under hang thereof until the accumulation drops from the edge 9, into the trough 10, while the silt and other refuse matter flow off from the end 8, and drop beyond the trough 10, as waste matter. The plates 14, have enough uphill slant to prevent their being swung free from the plate 7, by the current of slush. The gathering plates 14, hung alternately as described would still present their surfaces to the flowing slush to gather the metal that is in suspension above the bed plate if their ends were not bent obliquely as at 15, but were left in plane to meet the bed plate 7, in lines square across it, yet that form would impede the desired rapid flow of slush which produces the best results. The

hamper-board 16 backs up the top current of the slush to some extent and forces it into contact with the table, in a final effort to bring all the fine metal in contact with the mercury for amalgamation. When the plates 14 become loaded with amalgam they may be removed from the table and the amalgam be gathered from them and from the table plate 7, by usual means. The described means for bringing the slush while in fairly rapid flow, to come in contact with a great deal of surface covered with mercury accomplishes the first two points of my stated object, thoroughness and expedition in recovering precious metals; and arranging for a large portion of the amalgam to deliver itself automatically before cleaning of the plates becomes necessary, greatly economizes the manual labor.

I claim:

1. A slanting copper-faced amalgamating table; obstructing plates hung with spaces

between them in successive lines across over the table, the plates of each line being located opposite the spaces between the plates of the adjacent line, the whole width of the lower portion of each plate of one line slanting obliquely to the right along the table, and the corresponding portion of each plate of the next line slanting obliquely to the left. 25 30

2. In an amalgamator, a slanting, copper-faced table; a series of plates depending upon the table in successive lines across it, the line of contact of the whole width of each plate with the table slanting obliquely 35 to the line of the table, the slant of one line of plates being to the right and of the next line to the left.

In testimony whereof I affix my signature in presence of two witnesses:

WILLIAM W. DILL.
